UNITED STATES PATENT OFFICE

WERNER LÖBLICH AND HELMUTH LÖBLICH, OF DRESDEN, GERMANY

BOX-CLOSING DEVICE

Application filed July 8, 1929, Serial No. 376,593, and in Germany November 9, 1926.

The present invention relates to a device for closing boxes by means of band iron and a sleeve surrounding the ends of the iron.

Box closures, in which the ends of the band iron are surrounded by a sleeve and the latter as well as the ends provided with ribs by a press tool, are known to the art. It is further known to provide ribs of rectangular cross section, but the latter feature is found in the known devices only in connection with finger-like bends in the edge of the sleeve and ends.

According to the present invention, the ribs are arranged obliquely to the longitudinal edges of the sleeve and ends so that the forces of axial tension within the band iron ends are resolved into two component forces. One of these component forces acts perpendicularly to the rib and is perceptibly smaller than the original force so as to reduce considerably the danger of stretching the rib, while the other component force acting in the direction of the walls of the rib tends to shift the band iron ends in the sleeve laterally until they hug the edges of the latter. Moreover, this component force finds expression in two sub-components, one of which acts perpendicularly to the edge of the sleeve chiefly in the form of frictional pressure and exerts too little force to bend up the sleeve while the other sub-component acts parallel to the edge of the sleeve and causes the band iron ends and the sleeve to become inter-wedged. The connection effected according to the invention is perfectly firm, while the oblique position of the rib compared with the cross ribs extending perpendicularly to the edge of the sleeve in the closures of known type increases considerably the resistance of the joint relative to the axial forces.

In this simple manner the sleeves can be protected against being bent up and having the ends slip out.

The invention is illustrated in the accompanying drawing, in which Figure 1 is

a top view of the device; Fig. 2, a section on the line A—B; Figs. 3 and 4 are views of the sleeve; Fig. 5a is a top view of the device immediately after the formation of the rib; and Fig. 5b, a view of the device after the formation of the rib, the bands having moved along the rib to the edges of the sleeve. Figs. 6 and 7 show a modification.

Referring to the drawing, 1 indicates the lower band, 2 the upper one. 3 indicates the sleeve. 4 are the pressed ribs. 5 designates the wire arranged in front and 6 the wire in the rear. In Fig. 5a the joint is shown from above with the lengths of band iron 1 and 2 disposed one on top of another and the oblique rib 4 pressed on to the sleeve 3. On the bands 1 and 2 act the forces a_1 and a_2 tending to break the joint. The illustration further shows how the force a_1 is separated into the component forces b and c at the oblique rib 4. The same effect in opposite direction is brought about by the force a_2 , the components of this force being not shown, however, in the interest of greater clearness of the illustration.

Fig. 5b shows the same closure from above, but after the component forces b and c shown in Fig. 5a have done their work. The component force c has shifted the band 1 along the oblique rib 4 up to the edge of the sleeve.

Fig. 5b further shows how the component force c after shifting the band up to the edge of the sleeve is divided again into the component forces d and e .

The same happens to the band 2, though in opposite direction, the corresponding component forces being omitted in the drawing for the sake of clearness.

Fig. 5b therefore shows how the shifting effect on the bands 1 and 2 has come to an end by the inter-wedging of the bands within the sleeve in opposite directions so that it is impossible to push the bands 1 and 2 out of the sleeve 3.

This closing device can be used not only for boxes but for all kinds of packings where band iron or wire are used for effecting a closure.

We claim:—

In a box closing device the combination of overlapping ends of a band iron and a sleeve member enclosing said ends, the sleeve having a rib extending obliquely to its longitudinal axis and said ends having interfitting ribs nested in the rib of the sleeve.

In testimony whereof we have affixed our signatures.
